(57) **CLAIM**

The ornamental design for a folding tool with socket, as shown and described.

DESCRIPTION

FIG. 1 is a top perspective view of a folding tool with socket, showing my new design, shown in an expanded configuration;

FIG. 2 is a bottom perspective view of the tool in an expanded configuration;

FIG. 3 is a first side elevation view of the tool in an expanded configuration;

FIG. 4 is a second side elevation view of the tool in an expanded configuration;

FIG. 5 is a first end elevation view of the tool in an expanded configuration;

FIG. 6 is a second end elevation view of the tool in an expanded configuration;

FIG. 7 is a top plan view of the tool in an expanded configuration;

FIG. 8 is a bottom plan view of the tool in an expanded configuration;

FIG. 9 is a top perspective view of the tool in a retracted configuration;

FIG. 10 is a bottom perspective view of the tool in a retracted configuration;

FIG. 11 is a first side elevation view of the tool in a retracted configuration;

FIG. 12 is a second side elevation view of the tool in a retracted configuration;

FIG. 13 is a first end elevation view of the tool in a retracted configuration;

FIG. 14 is a second end elevation view of the tool in a retracted configuration;

(Continued)

FIG. 15 is a top plan view of the tool in a retracted configuration; and,
 FIG. 16 is a bottom plan view of the tool in a retracted configuration.

In the drawings, the broken lines illustrate portions of the folding tool with socket which form no part of the claimed design.

1 Claim, 11 Drawing Sheets
